(57) **CLAIM**

The ornamental design for a digital camera stand, as shown and described.

DESCRIPTION

FIG. 1 is a perspective view of my new design for a digital camera stand;

FIG. 2 is a side view of my new design for a digital camera stand;

FIG. 3 is a front view of my new design for a digital camera stand;

FIG. 4 is a top plan view of my new design for a digital camera stand;

FIG. 5 is a back view of my new design for a digital camera stand; and,

FIG. 6 is a bottom plan view of my new design for a digital camera stand.

The broken lines showing the Universal Serial Bus extension cord going into a digital camera stand with the outlet plug within the top section of the stand and leg members are for illustrative purposes only and form no part of the claimed design.
